UNITED STATES PATENT OFFICE.

WILLIAM ARNOLD LEWIS, OF CHICAGO, ILLINOIS, ASSIGNOR TO HOLLOW-AXLE MANUFACTURING COMPANY.

IMPROVEMENT IN WAGON-AXLES.

Specification forming part of Letters Patent No. 108,607, dated October 25, 1870; reissue No. 4,584, dated October 10, 1871.

To all whom it may concern:

Be it known that I, WILLIAM ARNOLD LEWIS, of Chicago, in the county of Cook, and State of Illinois, have invented certain Improvements in Wagon-Axles, of which the following is a specification:

In the drawing, Figure 1 is a longitudinal sectional view of the spindle and part of the axle. Fig. 2 is a front elevation of a forward axle on a smaller scale; Fig. 3, a cross-sectional view at x x , Figs. 1 and 2; Fig. 4, a cross-sectional view at y y , Fig. 2.

The first improvement I claim to have made is in the use of a pipe or hollow tube, a , having the ends swaged to a taper to form the journal or spindle d without the use of skeins or other external additions, as bearings, for the boxes to wear on, as shown in Fig. 1. The spindle d may be case-hardened to make it more durable. The wrought-iron collar c is shrunk on to form a butting-ring or shoulder for the hub to run against. Another improvement I claim to have made is in the king-bolt clip and the arrangement of the bolt at the center of the axle. The king-bolt i passes through the clip m , which is held in place

by the bolts o . The upper part of the clip furnishes a seat for the end of the reach, and the whole arrangement strengthens the axle at the center, as it is not necessary to have a hole entirely through the axle at that point, as is shown in Fig. 4. The collars c are furnished with the lugs or hinges r for the thills, thus saving another set of thill-clips. b is a plug welded into the ends of the axles to receive the nut which holds the wheel.

Having thus described my invention, what I claim as new, and desire to secure by Letters Patent, is—

1. A wagon-axle made from tubing by swaging taper spindles upon the ends.
2. The combination of the clip m , bolts o , king-bolt i , and axle a , constructed and arranged substantially as and for the purposes set forth.
3. The combination of the collar c , hinge r , and axle a , constructed and arranged as and for the purposes set forth.

WM. A. LEWIS.
